(57) **CLAIM**

The ornamental design for a wind turbine rotor as shown and described.

DESCRIPTION

1. Wind turbine rotor
2. Wind turbine rotor
- 1.1 : Front
- 1.2 : Back
- 1.3 : Right
- 1.4 : Left
- 1.5 : Top
- 1.6 : Perspective
- 2.1 : Front
- 2.2 : Back
- 2.3 : Top
- 2.4 : Right
- 2.5 : Left
- 2.6 : Perspective

The wind turbine rotor is shown with a symbolic break in its length. The appearance of any portion of the article between the break lines forms no part of the claimed design.
